GAS FURNACE WITH ELECTRICALLY IGNITED PILOT

Arnold V. Halda, Kansas City, Mo.

Application July 24, 1945, Serial No. 606,760

2 Claims. (Cl. 158—115)

1

This invention relates to igniting systems for fluid burners, and more particularly to an electrical igniting system for a gas burner.

A main object of the invention is to provide an electrical igniting means for a gas burner, such as is employed in gas heating furnaces, to supplement the conventional pilot light and to insure that the pilot light will remain burning when the main gas supply to the burner is turned off.

A further object is to provide a novel and improved igniting means for a gas furnace burner wherein a spark gap is employed as a supplemental igniting device, said spark gap also functioning to reignite the pilot burner should said pilot burner become extinguished upon turning off the main gas supply to the gas burner, or by a sudden draft.

Further objects and advantages of the invention will appear from the following description and claims, and from the accompanying drawing wherein:

The figure is a side elevation partly in section illustrating an igniting system for fluid burners constructed in accordance with my invention.

Referring to the drawing, 1 designates the main burner of a gas furnace, the supply of gas to said burner being regulated by a solenoid valve 2 which is energized, as required, by a suitable control circuit, to admit fuel to burner 1. A pilot burner 3 is employed to ignite the gas at main burner 1, said pilot burner being normally continuously lighted. However, it is frequently found in conventional structures that the flame at pilot burner 3 will be extinguished when the solenoid valve 2 closes to shut off the supply of gas to main burner 1, resulting in a dangerous escape of gas from the pilot burner and a highly dangerous escape of gas from the main burner when the solenoid valve reopens and the main gas flow fails to ignite.

To overcome the possibility of the pilot burner remaining extinguished and also to supplement the igniting action of the pilot burner when valve 2 is opened, I provide an electrical igniting system comprising a spark gap 4 positioned adjacent pilot burner 3, said spark gap being energized responsive to the opening or closing of valve 2. In the particular construction shown in the drawing, the top portion 5 of the solenoid casing of valve 2 is extended on one side to provide a support for a pivotally mounted switch arm 6, said arm being loosely secured at an intermediate portion thereof to an insulating stud 8 secured to the top end of the solenoid plunger 7 so as to be raised thereby when the solenoid is energized. Sup-

ported at the other side of top portion 5 is an insulating strip 9 carrying a pair of contacts 10 and 11 adapted to be sequentially momentarily engaged by the end of switch arm 6 as the solenoid valve is energized and to be momentarily engaged in reverse order when the solenoid valve is de-energized. Contacts 10 and 11 are connected to a primary terminal of an induction vibrator coil 12, the other primary terminal thereof being grounded. A secondary winding terminal of coil 12 is connected to one of the spark gap electrodes, the other terminal of the secondary winding and the other gap electrode being grounded. Switch arm 6 is connected to one secondary terminal of a step-down transformer 13, the other secondary terminal being grounded, and the primary winding thereof being connected to the house lighting mains.

When the solenoid valve 2 becomes energized switch arm 6 will be raised and momentarily close the primary circuit of coil 12 at contact 10, opening the circuit as it continues its upward movement and momentarily closing the circuit as it passes contact 11. This produces a shower of sparks at gap 4 which supplement pilot burner 3 in igniting the gas at burner 1. When solenoid valve 2 becomes de-energized, switch arm 6 moves downwardly through the dotted positions shown in the drawing and again induces sparks at gap 4 which reignite pilot burner 3 in the event that said pilot burner has become extinguished by the cutting off of the main gas supply to burner 1 or by a sudden draft. The reignition of pilot burner 3 is thus assured.

The make-and-break arrangement of switch arm 6 with respect to contacts 10 and 11 is such that the spark gap will be energized only when the solenoid valve 2 is being opened or closed. Under steady state conditions gap 4 is de-energized.

While a specific embodiment of an ignition system for a gas furnace burner has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. In a gas furnace, a main burner, a pilot burner positioned adjacent the main burner, means for continuously supplying gas to said pilot burner, a pair of electrodes positioned adjacent the pilot burner and defining a spark gap, a device for supplying high voltage current, said

device having its output terminals connected to said electrodes, a low voltage supply circuit for energizing said device, a normally closed control valve for said main burner, a solenoid, a plunger for said solenoid, means connecting said plunger to said control valve, said plunger being formed and arranged to open said valve responsive to the energization of said solenoid, a switch arm carried by the plunger, a plurality of contacts arranged to be momentarily successively engaged by said switch arm during the movement of said plunger to valve-opening position and to be momentarily successively engaged in reverse order during the movement of said plunger to valve-closing position, and means connecting said switch arm and said contacts in series in said low-voltage supply circuit of said high voltage device, said switch arm being free of engagement with any of its contacts when the valve is either in its fully opened or in its fully closed position.

2. In a gas burner, a main burner, a pilot burner positioned adjacent the main burner, means for continuously supplying gas to said pilot burner, a pair of electrodes positioned adjacent the pilot burner and defining a spark gap, a device for supplying high voltage current, said device having its output terminal connected to said electrodes, a low voltage supply circuit for

energizing said device, a normally closed control valve for said main burner, actuating means for said control valve, a switch arm operable by said actuating means, a plurality of contacts arranged to be momentarily successively engaged by said switch arm during the movement of said actuating means to valve-opening position and to be momentarily successively engaged in reverse order during the movement of said actuating means to valve-closing position, and means connecting said switch arm and said contacts in series in said low voltage supply circuit of said high voltage device, said switch arm being free of engagement with any of its contacts when the valve is either in its fully open or in its fully closed position.
